(57) **CLAIM**

The ornamental design for a eye mask with Bluetooth headset, as shown and described.

DESCRIPTION

FIG. 1 is a front, right and top perspective view of a eye mask with Bluetooth headset, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the eye mask with Bluetooth headset in another state.

The broken lines depict portions of the eye mask with Bluetooth headset that form no part of the claimed design.
